UNITED STATES PATENT OFFICE.

SAMUEL T. HENSEL, OF DENVER, COLORADO.

APPARATUS FOR THE MANUFACTURE OF SIMPLE SYRUP.

No. 912,959.

Specification of Letters Patent.

Patented Feb. 16, 1909.

Application filed April 18, 1908. Serial No. 427,820.

To all whom it may concern:

Be it known that I, SAMUEL T. HENSEL, a citizen of the United States, residing in the city and county of Denver and State of Colorado, have invented certain new and useful Improvements in Apparatus for the Manufacture of Simple Syrup; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in apparatus for the manufacture of simple syrup.

My improved construction consists of an outer vessel or receiver adapted to contain 20 the syrup; an inner container in which the sugar is placed; and a vessel centrally located within the sugar container and suspended above the bottom of the same. The outer receiver is provided at the bottom with a 25 faucet, or other means, for drawing off the syrup. The sugar container is suspended within the outer receiver, and its side wall near the bottom is perforated and provided with a covering of canvas or other suitable 30 pervious material. The inner vessel has a perforated bottom and impervious walls above the bottom.

Having briefly outlined my improved construction I will proceed to describe the same 35 in detail, reference being made to the accompanying drawing, in which is illustrated an embodiment thereof.

In this drawing, Figure 1 is a vertical section taken through my improved apparatus. 40 Fig. 2 is a perspective view in detail of the canvas strip applied to the perforated portion of the wall of the sugar container. Fig. 3 is a detail view of the sugar container. Fig. 4 is a similar view of the water receptacle or 45 the vessel located within the container. Fig. 5 is an underneath view of the construction shown in Fig. 4, or a view looking in the direction of arrow 5 in said figure. Fig. 6 is a top view in detail of one of the suspension 50 brackets applied to the water container. Fig. 7 is an extended view in detail of the canvas device applied to the sugar container. Fig. 8 is a clamping ring employed to secure the

canvas applied to the bottom of the water container. Fig. 9 is a view similar to Fig. 7, 55 with the clamping rings omitted.

The same reference characters indicate the same parts in all the views.

Let the numeral 5 designate the outer receptacle adapted to receive the simple syrup 60 6. Near the top of the receptacle 6 are formed vent perforations 7 which are covered by hoods 8 applied to the wall of the receptacle and extending downwardly from the perforations 7, whereby the latter are protected from the entrance of dust or other foreign particles of matter. The receptacle 5 is provided at the bottom with an outlet orifice 65 in which is inserted a faucet 9 for drawing off the simple syrup.

Suspended within the receptacle 5 is the container 10, which is frustum shaped, being largest at the top and tapering downwardly therefrom. At the upper portion of the container is formed a circumferential bead 12 75 which engages the top of the receptacle 5, this bead being so located as to suspend the container within the receptacle 5 in such a manner that the bottom of the container is a suitable distance above the bottom of the receptacle. The top of the container extends above the bead 12, as shown at 13, and is closed by a covering 14. The wall of the container, except for a short distance above the bottom, is impervious; however, a portion 80 15 of the wall near the bottom is perforated and covered by a canvas strip 16. This canvas strip is secured to upper and lower metal clamping rings 17. These rings are provided with outwardly projecting 85 lugs 18, which are perforated to receive clamping screws 19, whereby the canvas may be tightly secured to the perforated portion of the container. The wall of the container above the perforated portion is provided 90 with interiorly projecting circumferential beads 20, which form rests or stops for arms 21 projecting outwardly from rings 22, secured to the water container 23. These rings and arms serve as brackets, the outer 95 extremities of the arms being bent, as shown at 24, and engaging the beads 20 of the sugar container, whereby the water container or receptacle is suspended within the sugar container, so that the bottom of the water 100 receptacle is a suitable distance above the

105

2
bottom of the sugar container. As shown in the drawing, the water receptacle 23 has its lower portion enlarged, as shown at 25, its bottom being perforated, as shown at 26, 5 and provided with a canvas covering 27, which is turned upwardly to engagement with the vertical wall of the enlarged portion, and secured in place by a clamping ring 28.

10 From the foregoing description the use of my improved device will be readily understood. Assuming that the sugar container 10 is suspended in the receptacle 5, as shown in Fig. 1 of the drawing, and that the water 15 container is suspended within the sugar container, as shown in the same figure, a suitable quantity of sugar 29 is placed in the container 10, as shown in the drawing. This quantity of sugar may practically fill 20 the container 10, if desired. The receptacle, or container 23, is then supplied with water 30. This water passes through the perforated bottom 26, and the canvas or mesh covering 27, at the bottom of the receptacle 25 23, and seeps or percolates through the sugar within the container 10, forming a layer of suitable thickness below the bottom of the water container or receptacle. As the water passes downwardly through the sugar, it 30 dissolves the sugar and becomes saturated therewith, finally passing through the perforated side wall 15 of the container, and the outer canvas covering 16, and passing thence into the syrup receptacle 5.

35 It will be understood from the construction and arrangement shown in the drawing, that, as the water dissolves the sugar in the lower part of the container 10, the dry, or practically dry sugar above, will move downwardly to take the place formerly occupied by the dissolved portion; hence, the operation may be continued until practically all of the sugar within the container 10 has been dissolved or used in the formation of syrup, 45 which passes into the receptacle 5, as heretofore explained. This syrup may be drawn off through the faucet 9, as occasion may require.

It is evident that the canvas or other suitable mesh material 16 may be secured to the perforated portion of the sugar container in any suitable manner. It will be understood that it is not necessary that this strip should be metal bound, as illustrated in 55 Fig. 7 of the drawing. In any event nothing is claimed upon the special material employed, its only function being to provide a strainer outside of the perforated portion of the container, of sufficiently fine mesh to 60 perform the function suitably.

There is a decided advantage in perforating the outer wall of the sugar container above the bottom, and leaving the bottom thereof impervious. If the bottom is 65 perforated, it is necessary to cover it with a

strainer cloth, and in practice this sags downwardly and the solid sugar works through the perforations and collects between the perforated bottom of the container and the strainer, and oftentimes clogs the apparatus, since the sugar thus located is in contact only with the syrup or the water fully saturated with the sugar, and therefore will not dissolve. Furthermore, by having the bottom unperforated, in case there are solid 75 impurities in the sugar, this bottom forms a support therefore, and does not tend to clog the pervious zone of the container above the bottom. If the bottom of the container were pervious, and relied upon to form a passage for the syrup, solid impurities would have a tendency to clog the passage. By providing the container with a perforate zone above the bottom, all these difficulties are overcome, as will be readily observed. 80

In Fig. 9 of the drawing, the canvas strip or strainer is designated 16^a and it is provided at its opposite extremities with apertured lugs 18^a. At one extremity the strip extends beyond the lugs, as shown at 18^b. 90 When the device is in use, this extension 18^b is overlapped by the opposite end of the device, thus closing the space between the two sets of lugs when the device is applied. The strainer 16^a may be clamped to the container by the use of bolts or screws in the same manner as the metal bound canvas strip shown in Fig. 2. By using the form of construction shown in Fig. 9, it becomes practicable to draw the strainer more 95 tightly against the perforated portion of the container, thus making it practically impossible for any sugar to work between the wall of the container and the strainer.

Having thus described my invention, what I claim is:

1. In apparatus for the manufacture of simple syrup, the combination of an outer receptacle for the syrup, a sugar container suspended within the outer receptacle, the 110 said container having a portion of its wall above the bottom perforated, the perforated portion being confined to the lower half of the wall, and provided with a covering of mesh material, the bottom of the sugar container being impervious, a water receptacle 115 centrally located within the sugar container, the lower portion of the water receptacle being perforated, and its bottom supported a suitable distance above the bottom of the 120 container, the pervious portion of the water receptacle being provided with a covering of suitable mesh material, substantially as described.

2. In apparatus for the manufacture of 125 simple syrup, the combination of an outer receptacle adapted to contain the syrup, a sugar container suspended within the outer receptacle and having an impervious bottom and having the lower portion only of the 130

wall perforated and covered with a mesh material, a water container centrally supported within the sugar container, and having a perforated bottom provided with mesh material, means for clamping the mesh material to the water container and means applied to the latter and engaging the inner wall of the sugar container, whereby the

water container is suspended within the sugar container, substantially as described. 10

In witness whereof I affix my signature in presence of two witnesses.

SAMUEL T. HENSEL.
